UNITED STATES PATENT OFFICE.

WILLIAM FITZ CHARLES MASON McCARTY, OF EAST PLEASANTVILLE, NEW YORK.

COMPOSITION OF MATTER TO BE ADDED TO INTERNAL-COMBUSTION-ENGINE FUELS AND TO BE USED FOR OTHER PURPOSES.

1,167,770.

Specification of Letters Patent.

Patented Jan. 11, 1916.

No Drawing.

Application filed August 19, 1913. Serial No. 785,583.

To all whom it may concern:

Be it known that I, WILLIAM F. C. M. McCARTY, a citizen of the United States, residing at East Pleasantville, in the county 5 of Westchester and State of New York, have invented certain new and useful Improvements in Compositions of Matter to be Added to Internal-Combustion-Engine Fuels and to be Used for other Purposes, of which 10 the following is a specification.

This invention relates to a novel composition of matter for use in the arts and particularly for use as a solvent of oils, fats, waxes, wool fat and the like, and for the 15 prevention and removal of carbon deposits, scale or like incrustations in the cylinders of internal combustion engines.

In the preferred embodiment of my invention, I provide a mixture of acetone, 20 ether, (either ethyl or methyl ether) hydrogen dioxid and methyl nitrate, thereby producing a composition which is freely mixable with oils such as hydro-carbon or mineral oils, and which may be used as a solvent 25 therefor. To this mixture may be added a small quantity of a solution of nitro-glycerin in ethyl alcohol where the composition is to be used for the prevention or removal of deposits in internal combustion engines.

30 The proportions in which the materials are brought together is preferably as follows: acetone, 1 gallon; ethyl ether, 3 to 5 gallons; hydrogen dioxid, 12 ounces; methyl nitrate, 4 ounces.

35 Where nitro-glycerin is employed in the mixture it is added thereto in the proportions of one-half ounce of nitro-glycerin dissolved in a quart of ethyl ether to six gallons of the mixture.

40 In producing my composition, I prefer to first add the hydrogen dioxid to the acetone. I stir these materials until a homogeneous mixture or solution is obtained. I then add the methyl nitrate previously dissolved in 45 from five to ten times its weight of ethyl ether. The ethyl ether is then added and the composition is ready for use.

Where nitro-glycerin is employed in the mixture, it is preferably added last.

50 If I employ methyl ether in place of ethyl ether it is added in a gaseous state to the acetone as long as it will dissolve freely therein at ordinary atmospheric temperature or a similar quantity of the methyl

ether in a liquefied condition may be added 55 to the acetone.

In using my composition for the removal of deposits from the cylinders of internal combustion engines, the composition is placed in the engine cylinders and is prefer- 60 ably allowed to remain therein for several hours, the engine crank being rotated from time to time to move the pistons in the cylinders. The composition may then be drawn off, but better results are obtained 65 by starting the engine and permitting the small amount of the composition in the cylinders to be ignited, the high temperature resulting tending to consume the remaining carbon. I may however, advantageously 70 allow a small amount of my composition to be drawn into the engine cylinders with the fuel or I may add the composition to the fuel itself before it is drawn into the engine cylinders, in which case it is added to 75 the fuel in the preferred proportion of from one to five parts of the composition to ten parts of the fuel, although the proportion in which the composition is added to the fuel may be widely varied, a smaller 80 or larger proportion being employed. The particular amount added in each case must of course depend upon the observed characteristics of the mixture; that is, the way in which it acts in the engine cylinder. 85 The various oil fuels, of course, act quite differently in the cylinders of internal combustion engines using liquid fuel. Where my composition is added to the fuel the resulting solution may be separately piped to 90 the manifold but the composition is preferably mixed with the main body of the fuel and drawn therewith into the motor through the carbureter.

While I have described in detail the pre- 95 ferred practice of my invention, it is to be understood that the proportions of the ingredients may be widely varied and that equivalents of such ingredients may be em- 100 ployed, without departure from the spirit of my invention or the scope of the subjoined claims.

Having described my invention, I claim:—

1. A composition of matter for the purposes specified comprising acetone, ether, 105 hydrogen dioxid and methyl nitrate.
2. A composition of matter for the purposes specified comprising acetone, ether,

hydrogen dioxid, methyl nitrate and a high explosive.

3. A composition of matter for the purposes specified comprising acetone, ether, 5 hydrogen dioxid, methyl nitrate and nitro-glycerin.

In testimony whereof I affix my signature in presence of two witnesses.

WILLIAM FITZ CHARLES MASON McCARTY.

Witnesses:

JAMES L. CRAWFORD,
C. L. PARKER.
